UNITED STATES PATENT OFFICE.

JOHN M. RYAN, OF WATERBURY, CONNECTICUT, ASSIGNOR OF ONE-HALF
TO C. F. GOODWIN & SON, OF SAME PLACE.

DESIGN FOR A CARRIAGE-CANOPY.

SPECIFICATION forming part of Design No. 21,083, dated September 29, 1891.

Application filed July 6, 1891. Serial No. 398,606. Term of patent 7 years.

To all whom it may concern:

Be it known that I, JOHN M. RYAN, of Waterbury, in the county of New Haven and State of Connecticut, have invented a new Design 5 for a Canopy-Top for Carriages; and I do hereby declare the following, when taken in connection with accompanying drawing and the letters of reference marked thereon, to be a full, clear, and exact description of the same, 10 and which said drawing constitutes part of this specification and represents a perspective view of a canopy-top embodying my improved design.

My invention relates to a design for the 15 canopy-tops of carriages; and the design consists in the shape of the forward ends of the side flanges, which depend from the body of the top.

The body A of the top has the form of an 20 oblong rectangle and is longitudinally and laterally bowed. It has side flanges B B and a rear flange C, the upper ends of the said flanges merging into the adjacent edges of the top at a right angle therewith and their 25 lower ends being straight and in the same

plane. The forward ends of the side flanges are tapered to merge gracefully into the extreme forward end of the body of the top. As herein shown, the said tapering effect is secured by cutting the said ends away on 30 curved lines D D. I do not, however, limit myself to any particular way of securing the tapering effect.

I claim—

The design for the canopy-top for a carriage herein shown and described, the same comprising an oblong rectangular longitudinally and laterally bowed body and depending rear and side flanges, the forward ends of the side flanges merging in tapering lines 35 40 into the forward end of the said body, as set forth.

In testimony whereof I have signed this specification in the presence of two subscribing witnesses.

JOHN M. RYAN.
